UNITED STATES PATENT OFFICE.

DAVID SHATTUCK, OF CAMBRIDGE, AND JOHN S. SHATTUCK, OF MALDEN, MASSACHUSETTS, ASSIGNORS TO THE WHIPPLE FILE MANUFACTURING COMPANY.

IMPROVED MACHINE FOR CUTTING RASPS.

Specification forming part of Letters Patent No. 38,135, dated April 7, 1863.

To all whom it may concern:

Be it known that we, DAVID SHATTUCK, of Cambridge, in the county of Middlesex, and State of Massachusetts, and J. S. SHATTUCK, of Malden, in the county and State aforesaid, have invented certain Improvements in Machines for Cutting Rasps, of which the following is a full, clear, and exact description, reference being had to the accompanying drawings, making part of this specification, in which—

Figure 1 is a plan of a rasp-cutting machine with our improvements attached; Fig. 2, a side elevation, the gear E being removed to expose the parts behind it; Fig. 3, a front elevation of the same; Fig. 4, a view of the cams H⁴ and bar H⁵.

The machine represented in these drawings is designed for cutting blacksmiths' rasps, the teeth of which are disposed in rows across from side to side of the file. The driving-shaft A runs in standards B, rising from a table or bench, C, which is carried by a post, D. The blank a is secured to a suitable holder, b, and is fed up by a constant movement as the cutting proceeds in the following manner: A gear, E, upon the driving-shaft engages with an intermediate gear, E², upon a short shaft, E³, which also carries a bevel-wheel, E⁴, which drives a corresponding gear, E⁵, upon a vertical shaft, E⁶. A spur-wheel, E⁷, at the foot of this shaft, through the intermediate wheels, E⁸ and E⁹, drives a wheel, E¹⁰, in the center of which is a female screw, through which passes the screw-rod E¹¹, to the upper end of which is attached the holder, which carries the file, and thus, as the main shaft revolves, the file-blank is fed up past the cutter. The file-blank is supported by a rest, F, projecting from the top of the post D². The cams G, which operate the chisel or cutter, are carried by the driving-shaft A and operate upon an arm, G², projecting from the cutter-shaft G³, from which projects the cutter-head G⁴. The cutter is thrown after being released from its cam G by the spring G⁵, (seen dotted in Fig. 2,) and the arm G², as it descends, strikes against a spring, G⁶, by which the cutter is raised from off the blank the instant it has made its cut. The cutter-shaft G³ is pivoted to a carriage, G⁹, which is fed forward to carry the cutter across the blank

to form the rows of teeth in the following manner: H is a worm upon the driving-shaft, which engages with a worm-gear, H², upon a shaft running in the long box or bearing H³, upon the opposite end of which are the cams H⁴, against which rests a bar, H⁵, projecting from the cutter-carriage, and thus, as the main shaft revolves, the cams H⁴ feed the cutter across the blank. When the bar H⁵ escapes from one of the cams H⁴, the carriage is brought back ready to commence a new line of cuts by the spring I, which bears upon an arm, I², projecting from the shaft I³, from which rises an arm, I⁴, (seen in broken lines in Fig. 3,) the end of which works in an opening or hole in the cutter-carriage, or is otherwise suitably connected thereto, so as to keep the bar H⁵ constantly pressed against the cams H⁴. These cams are seen enlarged in Fig. 4. It has been stated that the teeth are placed in rows across the rasp, but it is essential that they be placed irregularly lengthwise of the rasp. It is for the purpose of effecting this irregular disposition of the teeth that we employ the cams H⁴. Were the carriage traversed across the blank by one and the same cam, the teeth would all be disposed one beneath the other through the whole length of the rasp, but by employing two or more cams of different shapes and height the teeth may be placed irregularly as required. The blank is kept down upon its rest by the presser f, the long arm f² of which is forced up by the spring f³. When the blank and its holder are to be removed from the machine, the presser is raised by forcing down its arm f² beneath the catch f⁴. As the blank is fed up by a constant motion, if the cutter was fed in a plane perpendicular to its line of motion, it is obvious that the teeth would be disposed in rows inclined to the sides of the rasp. To obviate this the cutter-carriage is caused to move upon inclined ways H⁶. This improvement is the invention of A. B. Southwick and H. E. Grandy, and need not be further described. The same may be said of the method herein adopted for holding the cutter or chisel i, which is formed of a bar of three-cornered steel, which passes through a mortise in the cutter-head, in which it is confined by another bar, i², in a mortise, cut at right angles to the other and a screw, r.

Neither of these improvements form any part of our invention. The intermediate wheel, E⁹, is carried by a short vertical shaft, E¹², upon which it runs freely. When a rasp has been finished and a fresh blank is placed in the machine, the wheel E⁹ is raised upon its shaft so as to disconnect the wheel E¹⁰ from the balance of the train. This wheel may thus be revolved rapidly in order to carry down the blank previous to starting the machine again.

What we claim as our invention, and desire to secure by Letters Patent in a machine for cutting rasps, is—

1. Arranging the cutter upon a traversing carriage and moving the same across the face of the rasp with a changing motion, for the purpose of placing the teeth in rows, as set forth.

2. In combination with the above, the cams H⁴, operating as set forth, for the purpose described.
